UNITED STATES PATENT OFFICE.

FREDRICK A. THURSTON, OF LYNN, MASSACHUSETTS.

SKIVING-MACHINE.

1,031,301.

Specification of Letters Patent.

Patented July 2, 1912.

Application filed April 28, 1911. Serial No. 623,843.

To all whom it may concern:

Be it known that I, FREDRICK A. THURSTON, a citizen of the United States, residing at Lynn, in the county of Essex and State 5 of Massachusetts, have invented new and useful Improvements in Skiving-Machines, of which the following is a specification.

This invention relates to a machine for skiving the counters and box toes of boots 10 and shoes.

The object of the invention is to provide a convenient and durable machine for the purpose specified which is capable of being adapted to different sizes and forms of 15 counters and box toes and which will skive the same with accuracy and despatch.

The invention consists in the combination and arrangement of parts set forth in the following specification and particularly 20 pointed out in the claims thereof.

Referring to the drawings: Figure 1 is a front elevation of my improved skiving machine. Fig. 2 is a plan view, partly broken away, of the same with the counter illustrated in full lines in readiness to be fed 25 between the feed rolls and against the knife, and a counter is also shown in dotted lines in position to be fed between the rolls by another feeding mechanism. Fig. 3 is a detail sectional elevation of the clutch shifting mechanism. Fig. 4 is a sectional elevation taken on line 4—4 of Fig. 1, looking toward the left in said figure. Fig. 5 is a 30 sectional elevation taken on line 5—5 of Fig. 1, looking toward the left in said figure. Fig. 6 is a detail sectional elevation illustrating the supporting arms for the matrix rolls. Fig. 7 is a detail plan view, partly broken away, illustrating the mechanism for 35 feeding box toes to the feed rolls. Fig. 8 is a sectional elevation taken on line 8—8 of Fig. 7.

Like numerals refer to like parts throughout the several views of the drawings.

The machine of my invention which I will now proceed to describe specifically consists 45 of two complete skiving mechanisms which are actuated by trains of gears, each train of gears being driven from a single driving shaft, and the said driving shaft also actuating a plurality of mechanisms for feeding the counter or box toe to the feed rolls and knives, said feeds being adapted to feed the counter either longitudinally thereof or 50 transversely thereof between said rolls.

In the drawings, 10 is the main frame of the machine supported upon suitable legs

11, 11. Upon the main frame 10 are slidably mounted two auxiliary frames 12 and 13. Said frames 12 and 13 are slidable 60 toward and away from each other upon guide rods 14, 14 fast to the main frame 10. Upon each of these auxiliary frames are mounted an upper feed roll 15 and a lower feed roll 16. The upper feed rolls 15 are 65 each provided with a recess to receive that portion of the counter or box toe which is to be skived, the portion projecting beyond said recess being cut off by a knife 17. The lower feed roll 16 is pressed upwardly 70 against the upper feed roll 15 by a spring (not shown in the drawings).

The counter or box toe is held in the matrix roll 15 by suitable fingers (not shown in the drawings, but well known to those 75 skilled in the art). The feed rolls, the knives and fingers referred to and the frames upon which they are supported are fully shown and described in a co-pending application for Letters Patent filed by me January 25, 1911, Serial No. 604,576.

A rotary motion is imparted to the feed rolls 15 and 16 upon the auxiliary frames 12 and 13 by the main driving shaft 18 which extends entirely across the machine 85 longitudinally of the two pairs of feed rolls and is journaled at its opposite ends in bearings 19, 19 in brackets 20, 20 fast to the frame of the machine. A rotary motion is imparted to the shaft 18 by the pulley shaft 90 21 which has fastened thereto a gear 22 which meshes into a gear 23 fast to the shaft 18. Gears 24, 24 are splined to the shaft 18 so that they can be moved longitudinally 95 thereof, and each of said gears meshes into a gear 25 fast to the shaft 26 journaled to rotate in a bearing 27 and having fastened to its inner end a gear 28 which meshes into a gear 29, fast to the shaft 30.

The upper feed roll 15 is fastened to the 100 shaft 30; the lower feed roll 16 is connected to and rotated by the shaft 26. The shaft 26 is journaled in a box 27 pivoted at 32 to the auxiliary frame 12 or 13, as the case may be, it being understood that the gearing 105 for rotating the feed rolls hereinbefore described is practically duplicated on each of the auxiliary frames 12 and 13, and the foregoing description, therefore, applies equally to the mechanism which rotates the feed 110 rolls at the right and the mechanism which rotates the feed rolls at the left of the machine, as viewed in Fig. 1.

The upper feed roll shafts 30 are jour-

naled in bearings 33, 33 on the auxiliary frames 12 and 13, and the adjacent ends of the upper feed rolls 15, 15 are journaled upon pins 34, 34 projecting into the interior 5 of said rolls 15, 15 from arms 35, 35 which are adjustably fastened to a supporting shaft 36 which, in turn, is fastened at opposite ends thereof to brackets 37, 37 on the auxiliary frames 12 and 13, respectively.

10 The counters are fed into the machine in a direction transversely thereof, as shown by the mechanism illustrated in Figs. 1, 2, 3, 4 and 5. The counter 38 is placed upon a work-table 39 and is fed between the feed 15 rolls, and by said feed rolls to the knife by means of a pusher 40 consisting of a T-shaped member, the body portion 41 of which is adjustably fastened to a slide 42 by a screw 43 which projects through a 20 slot 44 in the body portion 41 and has screw-threaded engagement with the slide 42. The arms 45, 45 of the T-shaped member each has a holder 46 fastened thereto by means of screws 47, 47, said holders 25 being adjustable longitudinally of the arms 45, 45 and fastened in place by the screws 47, 47.

Each of the holders 46 has mounted thereon a finger 48 which is adjustably fastened 30 to the holder 46 and hence to the arms 45 of which said holders form a part, by means of screws 49, 49, the forward ends of the fingers 48, 48 being adapted to rest against the edge of the counter 38 to feed the same 35 forward along the table and between the feed rolls.

The slide 42 is mounted upon two rods 50, 50 fast to brackets 51, 51 which, in turn, are fastened to the under side of the work- 40 table 39, and a reciprocatory motion is imparted to said slide and to the pusher attached thereto by a lever 52 which is pivoted at 53 to the frame of the machine and has a spring 54 attached to its lower end which 45 holds a cam roll 55 journaled upon said lever 52 against the periphery of an open cam 56.

The cam 56 is fastened to a shaft 57 which has bearings 58, 58 on the main frame of 50 the machine and is rotated by means of a gear 59 which is fastened to the shaft 57 by an arm 59', said arm 59' being pinned to the shaft 57 and fastened to the gear 59 by a screw 59" which extends through a slot 59' in the arm 59' and has screw-threaded engagement with the gear 59. The gear 59 meshes into a gear 60, the gear 60 meshing into a gear 61 which is fast to a shaft 62. The shaft 62 is rotated by a gear 63 which 55 meshes into a gear 64 fast to the shaft 18. Thus it will be seen that the shaft 18 rotates the trains of gears which actuate the two pairs of feed rolls and also actuates the train of gears which rotates the shaft 57, from 60 which a reciprocatory motion is imparted to 65

the slide 42, and the pusher 40 through the lever 52.

The driving shaft 18 and the gear 64 are disconnected from the train of gears 61, 60 and 59 by a clutch mechanism illustrated in 70 Figs. 1, 3 and 4, the purpose of disconnecting the driving shaft 18 from the said train of gearing being to enable the machine to be run without operating the feeding mechanism for pushing the counters or box toes 75 in between the feed rolls and yet allow the feed rolls to be rotated and the counters fed in between the feed rolls by hand in order to perform the skiving operation, and without the aid of the automatic feed device embodying the pusher hereinbefore described. 80

The clutch mechanism referred to consists of a lever 65 pivoted at 66 to the frame of the machine and connected to a slide rod 67 which has fastened thereto at the opposite end a forked arm 68 which engages a clutch slide 69 slidable longitudinally on the shaft 62, but prevented from rotating thereon by means of a pin 70 which is fast to the shaft 62 and projects into a slot 71 in the 90 slide 69. The clutch slide 69 has a head 72 thereon with a cam-shaped end 73 which is adapted to engage a pin 74 fast to the hub of the gear 63. The gear 63, it will be understood, is loosely mounted upon the shaft 95 62, while the gear 61 is rigidly fastened thereto. It will thus be understood that when the parts are in the position illustrated in Fig. 3, the gear 63 will be locked to the shaft 62 by means of the pin 74 and the 100 clutch slide 69 which it engages, as shown. When the lever 65 is moved toward the right (Fig. 3) the slide 69 is drawn toward the right and the cam-shaped end 73 thereof is drawn out of engagement with the pin 74 105 so that the gear 63 can rotate upon the shaft 62 freely.

Gages 75, 75 (Fig. 2) are provided against which the opposite ends of the counter 38 are adapted to bear, these gages acting to 110 guide the counter as it is being pushed in between the feed rolls. Said gages 75 are fastened to pins 76 which are adjustably fastened to the auxiliary frames 12 and 13 by means of screws 77. 115

When it is desired to feed the counter longitudinally thereof between the feed rolls in order to skive the counter lengthwise thereof, the counter is placed, as illustrated in dotted lines (Fig. 2) and the auxiliary 120 frame 12 is moved toward the right and a new matrix roll is placed upon the frame 12, and the counter is fed into the machine by a pusher 78 (Figs. 2 and 4). The pusher 78 is fastened to a slide 79 to which a reciprocatory motion is imparted by a lever 80 which is pivoted upon the rod 53 and has a rocking motion imparted thereto by a link 81, one end of which is pivoted at 82 to the lever 80, the other end of which is pivoted to 125 130

the crank-pin 83 upon the crank-arm 84, which crank-arm is fastened to the shaft 57. The lever 80 may also have a rocking motion imparted thereto by connecting one end 5 of the link 81 to a pin 85 fast to the lever 80, the other end of said link being connected to the crank-pin 86 fast to the crank-arm 87, said crank-arm being fastened to the shaft 62. When box toes are being fed, 10 the lever 80 is connected by the link 81 to the crank-pin 86. When counters are being fed longitudinally thereof, the lever 80 is rocked by the link 81 connected from said lever 80 to the crank-pin 83.

15 The gearing hereinbefore described is so proportioned that the shaft 62 is rotated once while the feed roll shaft 30 is rotated once and the shaft 62 is rotated twice while the shaft 57 is rotated once. In feeding 20 counters longitudinally thereof to the feed rolls it is necessary that the feed rolls should rotate twice, to feed one counter through therebetween. The reason for this difference in the relative rotations of the shafts 25 62, 57 and 30 is that when the counters are being fed in longitudinally thereof, the feed rolls have to make two rotations in order to pass the entire length of the counter therebetween, whereas when the counter is being 30 fed transversely thereof, or when a box toe is being fed between the rolls, it is only necessary for the feed rolls to rotate once during the passage of said box toe or counter therebetween, and thus by proportioning the 35 gearing so that the shaft 62 rotates twice while the shaft 57 rotates once, and the relative rotation of the shaft 62 and the shaft 30 being substantially the same, the desired result is obtained, whereby the counters and 40 box toes may be fed into the machine and the counters may be fed either longitudinally or transversely thereof, as may be desired.

The mechanism for actuating the pusher 45 78 is duplicated at the right and left sides of the machine, so that the counters can be fed longitudinally to the feed rolls on the auxiliary frame 12 and also to the feed rolls on the auxiliary frame 13. When box toes 50 are fed between the feed rolls, the mechanism illustrated in Figs. 7 and 8 is employed. The box toes 88 are placed in a pile upon the work-table 39 and a pusher 89 is fastened to the slide 79, said slide being reciprocated, as hereinbefore described, by a lever 80 and the rocking motion is imparted to the lever 80 by the link 81 connecting the lever to the crank-arm 87.

It will be seen that the relative time of 60 movement of the slide 42 to the matrix roll may be changed by loosening the screw 59² and rotating the gear 59 upon the shaft 57 the desired amount, and then fastening the arm 59' to the gear 59 by tightening the 65 screw 59². This will change the time when

the counter 38 is pushed in between the feed rolls relatively to the depressions in the matrix rolls. The time when the counter can be pushed in between the feed rolls can also be varied by loosening the screw 43 and 70 adjusting the pusher 40 relatively to the slide 42 and then tightening the screw 43.

The fingers 48, 48 may be adjusted longitudinally thereof to fit different shaped edges upon the counters which are to be fed. 75

The general operation of the machine hereinbefore specifically described is as follows: Assuming the parts to be in the position illustrated in Figs. 1, 2, 3, 4 and 5, and that it is desired to skive the ends of 80 the counter 38, said counter is placed upon the work-table, as illustrated in Fig. 2, with the fingers 48, 48 bearing against one edge thereof. The machine having been started, the feed rolls are rotated from the shaft 18 85 by means of the gears 24, 25, 28 and 29, and the counter is fed along the top of the work-table and in between the feed rolls, by the pusher 40. The same is then fed between the feed rolls and against the knife 17 90 to skive the opposite ends of said counter in a manner well known to those skilled in this art, a reciprocatory motion being imparted to the slide 42 by the lever 52 and cam 56, as hereinbefore described. 95

When it is desired to feed the counters into the machine longitudinally thereof, the pusher 78 is utilized, said pusher 78 having a reciprocatory motion imparted thereto by the lever 80, link 81 and crank 84. When it is desired to feed box toes into the machine to be skived the same are fed into the machine by the lever 80, link 81 and crank 87, together with the slide 79 and pusher 89. 100

Having thus described my invention, 105 what I claim and desire by Letters Patent to secure is:

1. A machine for skiving articles of sheet material having, in combination, a pair of feed rolls, one of said feed rolls constituting 110 a matrix, a knife with its cutting edge projecting between said rolls, a work-support adjacent to said feed rolls, a slide, a pusher on said slide adapted to engage one of said articles on said work-support and move 115 the same toward said feed rolls, a lever connected to said slide, two shafts, mechanism operatively connected with said shafts to drive them at relatively different rates of speed, and mechanism adapted to connect 120 said lever to either one of said shafts.

2. A machine for skiving articles of sheet material having, in combination, a pair of feed rolls, one of said feed rolls constituting 125 a matrix, a knife with its cutting edge projecting between said rolls, a work-support adjacent to said feed rolls, a slide, a pusher on said slide adapted to engage one of said articles on said work-support and move the same toward said feed rolls, a lever con- 130

nected to said slide, two shafts, mechanism operatively connected to said shafts to drive them at relatively different rates of speed, a crank on each of said shafts and a link adapted to connect either one of said cranks to said lever.

3. A machine for skiving articles of sheet material having, in combination, a pair of feed rolls, one of said feed rolls constituting a matrix, a knife with its cutting edge projecting between said rolls, a work-support adjacent to said feed rolls, a slide, a pusher on said slide adapted to engage one of said articles on said work-support and move the same toward said feed rolls, a lever connected to said slide, a driving shaft, two auxiliary shafts, gearing connecting said driving shaft to said auxiliary shafts and adapted to drive said auxiliary shafts at relatively different rates of speed, gearing connecting said driving shaft to said feed rolls, mechanism adapted to connect said lever to either one of said auxiliary shafts, and means to change the time of movement of said slide relatively to said matrix roll.

4. A machine for skiving articles of sheet material having, in combination, a pair of feed rolls, one of said feed rolls constituting a matrix, a knife with its cutting edge projecting between said rolls, a work-support adjacent to said feed rolls, a slide, a pusher on said slide adapted to engage one of said articles on said work-support and move the same toward said feed rolls, a lever connected to said slide, a driving shaft, two auxiliary shafts, gearing connecting said driving shaft to said auxiliary shafts and adapted to drive them at relatively different rates of speed, gearing connecting said driving shaft to said feed rolls, mechanism adapted to connect said lever to either one of said auxiliary shafts and mechanism adapted to throw said first-named gearing out of connection with said driving shaft.

5. A machine for skiving articles of sheet material having, in combination, a pair of feed rolls, one of said feed rolls constituting a matrix, a knife with its cutting edge projecting between said rolls, a work-support adjacent to said feed rolls, a slide, a pusher on said slide adapted to engage one of said articles on said work-support and move the same toward said feed rolls, a lever connected to said slide, and mechanism adapted to impart a rocking motion to said lever, said pusher consisting of a T-shaped member, the body portion of said T fast to said slide, and two fingers, one mounted on each arm, respectively, of said T, their free ends adapted to engage the edge of said piece of sheet material.

6. A machine for skiving articles of sheet material having, in combination,

feed rolls, one of said feed rolls constituting a matrix, a knife with its cutting edge projecting between said rolls, a work-support, adjacent to said feed rolls, a slide, a pusher on said slide adapted to engage one of said articles on said work-support and move the same toward said feed rolls, a lever connected to said slide, and mechanism adapted to impart a rocking motion to said lever, said pusher consisting of a T-shaped member, the body portion of said T fast to said slide, a holder fastened to each arm, respectively, of said T and adjustable longitudinally of said arms, and a finger mounted on each of said holders respectively and adjustable longitudinally of said body portion, the free ends of said fingers adapted to engage the edges of said piece of sheet material.

7. A machine for skiving articles of sheet material having, in combination, a pair of feed rolls, one of said rolls constituting a matrix, a knife with its cutting edge projecting between said rolls, a work-support adjacent to said feed rolls, a slide, a pusher adapted to engage one of said articles on said work-support and move the same toward said feed rolls, mechanism adapted to move said pusher toward and away from said feed rolls, said pusher consisting of a T-shaped member, the body portion of said T fast to said slide, and two fingers, one mounted on each arm, respectively, of said T, their free ends adapted to engage the edges of said articles of sheet material.

8. A machine for skiving articles of sheet material having, in combination, a pair of feed rolls, one of said feed rolls constituting a matrix, a knife with its cutting edge projecting between said rolls, a work-support adjacent to said feed rolls, a slide, a pusher adapted to engage one of said articles on said work-support and move the same toward said feed rolls and mechanism adapted to move said pusher toward and away from said feed rolls, said pusher consisting of a T-shaped member, the body portion of said T fast to said slide, a holder fastened to each arm, respectively, of said T and adjustable longitudinally of said arms, and a finger mounted on each of said holders, respectively, and adjustable longitudinally of said body portion and transversely of said arms, the free ends of said fingers adapted to engage the edges of said articles of sheet material.

In testimony whereof I have hereunto set my hand in presence of two subscribing witnesses.

FREDRICK A. THURSTON.
